UNITED STATES PATENT OFFICE.

DONALD G. ACKERLY, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

ABRADING MACHINE.

Application filed September 14, 1926. Serial No. 135,465.

My invention relates to abrading machines and more particularly to machines for abrading the surface of materials in disk form.

5 One object of my invention is to provide a machine for automatically abrading the surface of the elements used in rectifying apparatus wherein the rectifying function is performed by means of members composed of metal having a metal compound form thereon. These members are ordinarily of disk form and have an opening near the center thereof. In one type of rectifier the disks are composed of copper having 10 copper oxide formed thereon. In the manufacture of these disks the copper disk becomes coated on one surface with cuprous oxide and this oxide is in turn covered with cupric oxide. Before the rectifier can be 15 used the cupric oxide must be removed and it is also advantageous to remove as much of the cuprous oxide as is possible without injuring the contact surface of the copper and the cuprous oxide. I provide apparatus 20 for accomplishing this result effectively.

I will describe one form of apparatus embodying my invention, and then point out the novel features thereof in the claim.

In the accompanying drawing Fig. 1 is a 25 plan view, partially diagrammatic, showing one form of apparatus embodying my invention. Fig. 2 is a sectional view on the line II—II of Fig. 1. Fig. 3 is a sectional view of one form of abrasive sifting apparatus for use with the machine shown in Figs. 1 and 2. Fig. 4 is a sectional view on the line IV—IV of Fig. 3. Fig. 5 is a detail view showing, in side elevation, one of the grinding wheels of the apparatus illustrated in Fig. 1, together with the bracket which supports the shaft upon which the wheel is mounted.

Similar reference characters refer to similar parts in each of the several views.

45 Referring to Fig. 1, the reference character A designates a stationary supporting table which is itself supported by any suitable means not shown. Rotatably mounted on the table A is a disk B thinner than the 50 material which is to be abraded and pro-

vided with apertures 1 which are evenly spaced and are equidistant from the center of the disk. These apertures are slightly larger than the rectifier disks 2. The disk B is rigidly secured to a vertical shaft 3 55 which is driven by any suitable means not shown. As here shown, a collar 25, fastened to the shaft 3 by means of a pin 24, is secured to the disk B by means of rivets 26. Mounted above the disk B by means of 60 brackets 19 and on diametrically opposite sides of the center are two magazines M arranged to register with the apertures 1 in the disk B. When the disk B rotates, disks 2 drop into the apertures 1 and are carried 65 along.

The abrading operation is performed by two abrading wheels 4 and 4^a mounted above the disk B and spaced 180° apart. Wheel 4 is carried by a spindle 20 journalled in a 70 member 27 attached to the table A, as best shown in Fig. 5. In similar manner wheel 4^a is carried by a spindle 20^a journalled in member 27^a. The wheels 4 and 4^a are driven at a definite speed relation with respect to 75 the disk B by means of suitable gearing G here shown as a pinion 21 attached to shaft 3 and meshing with two gears 22 and 22^a rigidly attached to the confronting ends of spindles 20 and 20^a, respectively. The 80 wheels 4 and 4^a are made of any suitable rigid material and the outer peripheral surfaces are covered by rings 5 of resilient material such as rubber. Over each ring 5 is secured fine metal screening 6 which forms 85 the abrading surface. Small metal strips 17 secured to the table A are arranged to prevent the disks 2 from being thrown out of the apertures 1 during the abrading operation. Associated with each abrading wheel 90 is an abrasive reservoir R, which sifts abrasive material onto the disks 2 as they pass along from the magazines M to the abrading wheels.

95 The abrasive reservoirs R are provided with sifting mechanism which is shown in detail in Figs. 3 and 4. Each reservoir R has vertical side walls and a bottom arranged in the form of a hopper. The bot- 100

tom contains a slot 7 above which rotates a sifting mechanism composed of a plurality of rods 8 secured in two end members 9. The members 9 are mounted on a shaft 10 which is rotatably mounted in journals 11. The shaft 10 is arranged to be frictionally driven from the disk B by means of a wheel 12 having an outer surface 13 composed of some frictional material such as rubber. 10 When disk B rotates, the reservoir R being full of abrasive material, the shaft 10 is rotated and causes the rods 9 to stir the abrasive so that it falls downward between the rods 9 and through the slot 7 onto the disks 15 2 which are being carried along by the disk B.

The table A contains two apertures 16 through which the disks 2 pass after leaving the abrading wheels. Rods 15 placed beneath the apertures are arranged to collect the disks. The surplus abrasive is removed from the disk B by means of curved strips 14 which are secured to the table A by means of supporting strips 18, and frictionally engage the disk B as it rotates. 25

The operation of the device is as follows: The magazines M are filled with disks 2, the oxide surface being upward. Disk B is rotated in a counter clockwise direction as 30 shown by the arrow so that as seen in the drawing wheel 4 rotates in a clockwise and wheel 4^a in a counter clockwise direction. The lowermost disk 2 in each magazine drops into the first aperture 1 in disk B which 35 comes into registry with the magazine and is carried along under the reservoir R where it is supplied with abrasive material. The abrasive may be finely powdered emery or any other suitable material. The disk 2 40 then passes under an abrading wheel where the coating of cupric oxide and a part of the cuprous oxide are ground off to a flat surface, and then passes over an aperture 16 in the table A through which it falls and is 45 caught on the rod 15. The surplus abrasive material is removed from the disk B by the strips 14.

The speed of the disk B and of the wheels 4 and 4^a is so adjusted that all of the cupric oxide and as much of the cuprous oxide is 50 removed, as is possible without injuring the junction of the copper and the oxide. The size of wheel 12 may be varied so that the proper amount of abrasive is supplied to a disk 2 while it is passing beneath the 55 reservoir R. When the parts are properly proportioned the machine will furnish abraded disks as long as the magazines M and the reservoirs R are supplied with material. 60

Although I have shown and described only one form of abrading machine embodying my invention, it is to be understood that various changes and modifications may be made therein within the scope of the appended claim without departing from the 65 spirit and scope of my invention.

Having thus described my invention, what I claim is:

An abrading machine for oxide coated 70 metal disks comprising a flat horizontal supporting table having an opening therein, an apertured disk arranged to rotate in a horizontal plane adjacent the upper face of said table, a magazine mounted above said 75 rotatable disk for receiving a supply of said metal disks and supplying them one at a time to the apertures in said rotatable disk, an abrasive reservoir located over said rotatable disk adjacent the path of travel of 80 said apertures, an abrading wheel comprising a cylindrical member of rigid material, a layer of resilient material on the outer peripheral surface of said member, and a reticulated metallic covering on said layer, 85 means for driving said wheel to engage said metal disks successively as said rotatable disk is operated, means located above the opening in the table for removing abrasive material from the rotatable disk, and means 90 below such opening for collecting the abraded metal disks.

In testimony whereof I affix my signature.
DONALD G. ACKERLY.
